(57) **CLAIM**

The ornamental design for a chest drainage unit, as shown and described.

DESCRIPTION

FIG. 1 is a front left perspective view of a chest drainage unit according to my new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof; and,

FIG. 8 is a bottom perspective view thereof.

The broken lines shown in the drawings are for illustrative purposes only and form no part of the claimed design.
